UNITED STATES PATENT OFFICE.

MORTIMER F. BATES, OF BROOKLYN, NEW YORK, ASSIGNOR TO THE SPERRY GYRO-SCOPE COMPANY, OF BROOKLYN, NEW YORK, A CORPORATION OF NEW YORK.

TORPEDO DIRECTOR.

Application filed February 26, 1923. Serial No. 621,483.

This invention relates to torpedo control and has for its object the provision of an improved device for such control. More specifically, my invention relates to an automatically controlled device for ascertaining the proper moment of discharge of a torpedo to make a hit. While the particular device herein disclosed and described is primarily adapted and intended for use in connection with the launching of torpedoes, the principles involved are undoubtedly applicable to analogous usages, and my invention is not to be limited to torpedo usages alone, even though for the purpose of setting forth and defining my invention, I may be obliged to employ description and explanation in the more specific terms of this particular use.

The factors to be dealt with in a device where the interception of the course of an enemy ship is to be figured, are the course and speed of the enemy ship, the course of the torpedo carrier, the speed and range of the torpedo, the angle of discharge of the torpedo, the rudder set of the torpedo, the drift of tide or current and the correction of the sight line due to variations in the course of the ship.

In this device, an element known as the enemy course bar is to be set and maintained parallel with the course of the enemy ship, which considered in the instrument itself is tantamount to an angular adjustment in relation to the fore and aft line of the ship firing the torpedo.

An object of the present invention is automatically to maintain the position of the enemy course bar parallel to the course of the enemy ship, independently of the fore and aft line of the ship carrying the torpedo, so that whether the latter's course be varied or altered, the enemy course bar will maintain its factor in the angular set of the sight bar, as long as the enemy's course is unchanged. This result I accomplish by angularly displacing the enemy course bar a distance equal to the angular variation in the course of the ship carrying the torpedo, employing for this purpose a repeater motor actuated by a master gyroscopic compass.

Another object of my invention is to provide an efficient means for locking the enemy course bar and the compass card together, which comprises an electromagnetic clutch. The advantage of this arrangement is that

these members may be readily unclutched by simply operating a switch, when it is necessary to readjust the enemy course bar. Time is a very essential element, and by my invention, this operation is accomplished practically instantly.

My invention will be better understood from the following description taken in connection with the accompanying drawings and its scope will be pointed out in the appended claims.

In the drawings illustrating what I now consider the preferred form of my invention,

Fig. 1 is a plan view,

Fig. 2 is a side elevation with certain parts in section,

Fig. 3 is an enlarged sectional view illustrating the operating parts,

Fig. 4 is a sectional detail of Fig. 3.

Fig. 5 is an elevation of a modification of a portion of the Fig. 2 device, and

Fig. 6 is a diagram of the circuits.

Referring now to the drawings in which the numeral 1 indicates a cylindrical casing in which is mounted certain operating mechanism to be described in detail hereinafter. The casing is mounted in gimbal rings 2, 3 in the usual manner, and has secured thereto, such as by screw 4, a top plate 5 which is formed on its periphery with a flange 6 fitting over the edge of the casing 1. On this flange are graduations, as shown at 7 in Fig. 2, preferably from zero to 180° in both directions, the zero and the 180° mark being set in the true fore and aft line of the keel of the ship with the zero mark toward the bow thereof. This circle will therefore read in true angular relation to the fore and aft line of the ship. The plate 5 is also formed with a central opening 8, and an upwardly extending sleeve 9 concentric therewith. A sleeve 10 is rotatably fitted around the sleeve 9, and carries a bar formed on diametrically opposite sides thereof as shown at 11 and 11', which bar is termed the torpedo bar. This bar is intended to be set at the angle of the tube from which the torpedo is to be discharged and it therefore lies parallel to the course of the torpedo in the water. The end 11 is formed with a pointer 12 to cooperate with the scale 7, and the end 11' is formed with a flange 13 carrying a set screw 14 arranged to hold the

pointer 12 in fixed relation to the scale 7 in a manner readily understood. The end 11' of the torpedo bar is formed with an upwardly extending arm 15 which rigidly supports at 16 a scale which is calibrated to read knots per hour and indicating the speed of different torpedoes, the scale itself not being visible in the figure. The scale is on the upper surface of a hollow frame 17 arranged to accommodate a slide block 18, which is moved along the scale 16 by a screw 19, in a manner readily understood. As indicated above, the scale 16, in other words the frame 17, is rigidly secured to the arm 15 of the torpedo bar and is mounted in the same vertical plane as and parallel to said bar. Therefore, the slide block 18 may be set by the screw 19 for the speed of the particular torpedo which is to be fired.

20 Suitably journaled within the central opening 8 and the upper end of sleeve 9, such as by ball bearings 20 and 21, is a hollow sleeve 22 which carries a compass card 23, which is arranged to maintain the same position in azimuth by means of mechanism to be hereinafter described. Within the sleeve 22 is rotatably journaled a shaft 24 which carries a member 25 known as the enemy or pointer bar. The shaft 24 may be 25 journaled in the sleeve 22 by means of ball bearings as shown at 26 and at its opposite end in a frame 27 carried by the plate 5 as shown at 28. The enemy bar is intended to be disposed parallel to the course of the enemy ship against which the torpedo is to be directed. The enemy bar 25 carries a scale 29 graduated from the center outwardly in knots per hour, so that the slide block 30, which cooperates therewith in a 30 manner similar to the block 18 with respect to scale 16, may be set for the speed of the enemy ship, by means of the screw 31, as will be readily understood.

On the slide block 18 is rotatably journaled a shaft 32 which carries a sight bar 33, which passes through the slide block 30, as shown in Fig. 2 at 50, and gives the alignment for the point in the enemy's course which the enemy ship must occupy at the 35 moment of discharge of the torpedo in order that the torpedo may intercept the enemy ship.

As shown in Fig. 2, the sight bar 33 is loosely mounted on the shaft 32, and has an arm 34 projecting therefrom on which is rotatably mounted a graduated head 35, to cooperate with a pointer 36. The head 35 is secured to a screw indicated by the dotted line 37 which screw is in threaded engagement with an arm 38 of a sleeve 39 which is rigidly secured to the shaft 32. On the sleeve 39 is secured a pointer 40. It is therefore clear that the sight bar 33 is moved with the shaft 32, and that the pointer 40 and the sight bar 33 may be relatively dis-

placed through the rotation of graduated head 35. Any suitable type of scale may be provided to indicate the movement by the head 35 which may provide for correction of tidal influence on the torpedo and under 70 certain conditions, for the angle of a parallax resultant from the angular gyroscope set of the torpedo, and the parallax error due to the distance of the torpedo tube from the director.

In the instrument thus far described, if properly set and handled, the sight bar 33 points to the position which the enemy ship must occupy at the moment of discharge of the torpedo, in order to make a hit. If 80 provided with a telescope, the ship would be so sighted, and such an arrangement is shown in Fig. 5 in which the telescope 41 is shown pivotally mounted to rotate about an axis 42 normally at right angles to the sight 85 bar 33 on the shaft 32. The axis 42 may be supported by a pair of arms 43 secured to a base 44 which is arranged to fit the upper square end of the shaft 32 and held thereon by a screw cap 45. Normally, the telescope 90 and the bar 33 are sighted along the same line, but, as above pointed out, they may be relatively displaced by the rotation of the head 35 to make the corrections referred to.

Obviously, in below deck use, an actual 95 sighting of the bar 33 cannot be had. Furthermore, if the torpedo tube is a bow tube, that is, the axis thereof coincides with the fore and aft axis of the vessel, pointer 33 will give the correct reading on scale 23'. If, however, the torpedo tube is not a bow 100 tube but has its axis at an angle to the fore and aft axis of the vessel, then torpedo bar 12 is moved through this angle thus moving also pointer 33, and introducing an error. 105 To compensate for this error I provide the following adjustment.

For this purpose, the arrangement shown in Figs. 1 and 2 is provided in which the pointer 40 is mounted for reference to a circular card 46 which is rotatable on a ring 47 fixed on the square top of shaft 32. The card 46 has a double series of graduations 46' and 46''. The outer one 46' adjacent the pointer 40 has graduations corresponding to the sight circle 23', that is the graduations on the compass card 23, but graduated from the opposite points, to wit, clockwise from zero to 360° with the zero at six o'clock of the clock face and with its zero—180° line 110 always parallel with the fore and aft line of the ship. This provides for the correct reading of the pointer 40 which will thus indicate on the scale 46' that degree of enemy position which would be indicated by a pointer 115 radially run from the center of the periscope parallel to the sight bar 33, which would thus cut the scale 41 at the true degree of horizon which would correspond with the 120 reading of the periscope.

The scale 46" is concentrically arranged within the scale 46' on the ring 46 and has graduations reading from zero to 180° in both directions which are read referable to a pointed mark 48 arbitrarily located on one of the spokes of the ring 47. The scale 46" provides for a corrective setting of the secondary sight circle 46 according to the angle of the torpedo correction made by moving 5 the bar 11. The exact location of this pointer is immaterial, except that it and the scale should be so disposed that when zero of the scale 46" is opposite the pointer mark 48, the secondary sight circle 46 should have its zero 10 at six o'clock of the instrument, or in other words, on the aft end of the fore and aft axis of the instrument.

In case the torpedo tube is not a bow tube, as the example for which the arrangement 20 described is set, then obviously, setting the torpedo bar 11 at the angle of the torpedo tube will vary the sight bar 33 from the position it would occupy if the torpedo tube were a bow tube. For example, if the torpedo 25 do was to be fired from a starboard bow tube set at 45°, then the torpedo bar 11 would be turned to the starboard half way between the 40° and 50° mark, which would of course move the sight bar 33 laterally, inasmuch as 30 it is pivotally mounted on the torpedo bar 12.

In order therefore to correct what would otherwise be an error in the reading of the pointer 40, the secondary sight circle 46 is so moved in the direction opposite to that in 35 which the torpedo bar 12 has been moved, until the inner graduations 46" show half way between the 40° and 50° opposite the pointer 48. This will correct the reading of the pointer 40 on the secondary sight graduations 46" which will then indicate the exact 40 degree of horizon on which the enemy ship must be sighted to make the hit.

The above constitute the general operations and adjustments, but there are at least two 45 other factors for which adjustment must be made. These are the resultant drift of the torpedo in case of cross tide or the like, and secondly the angle of parallax which is variant depending upon the distance of the 50 enemy ship and the distance from the director to the tube, or the radial distance for a torpedo under gyro control or the resultant of any or all three.

These three corrections may be made by 55 separate adjustment or by a single net adjustment of the pointer 40 relative to the sight bar 33. This will add or subtract from the scale reading just that amount necessary to allow for the drift or angle or net correction of the tube. In the form shown this 60 is done through the head 35.

Since the torpedo has a limit of range, it is necessary that the point in the enemy's course at which the enemy ship is sighted 65 when the torpedo is fired may not be too

great to effect a hit. The distance at which the enemy ship may be sighted when the torpedo is fired depends upon its distance at that moment and the relation of its course to that which the torpedo is to take. If the interception of the line of the enemy's course with the line of the torpedo's course is at a point in excess of the range of the torpedo, no hit would be effected and the torpedo lost.

It therefore becomes necessary to know at 70 the moment when the enemy ship is sighted, and it is desired to launch the torpedo, whether the enemy ship is at a distance so that it will be within the range of the torpedo if fired. As different torpedoes have 80 different ranges and different speeds, it is necessary to have means by which these facts may be determined. This is accomplished by longitudinally channeling the sight bar 33 with an undercut grooving within which 85 may be slipped a strip of cardboard or celluloid 49. As many of these slips are provided as there are torpedoes of different range or speed, either or both, or blank strips of celluloid may be provided so that they 90 may be graduated for any torpedo. Each strip 49 has an indication of the range and speed of the torpedo with which it is to be used and each strip is scaled according to 95 the range and speed of the torpedo. These 95 scales are to be read with reference to a pointer mark 50 on the slide 30 of the enemy course bar 25.

When the instrument has been properly set with the proper scale 49 in place, the 100 officer in charge of the instrument while waiting for the enemy ship to come into the indicated position when the torpedo must be discharged, notes the enemy's distance as reported to him. By reference to the position 105 of the pointer 50 on the scale 49, he is able to judge in advance whether the enemy ship will probably be within range, and if at the moment of fire the enemy ship is announced to be at a distance greater.

By locating the scale on the sight bar, it is possible on account of its guided relation on the slide 30 on the enemy course bar 25 to use a graduated scale which will show 110 for the actual speed of the torpedo as set 115 on the scale 16 the limit of actual distance within which the enemy must be at the time of point of sight in order to have the enemy ship within the actual range of the torpedo on its course.

This scaling may be very simply effected by measuring the distance between the center of the pivot post 24 and the center of the pivot post 32 of the slide 18 on the torpedo tube bar 12 with said slide set with 120 the given speed of the torpedo. This distance is measured off and marked on the card from the center of the pivot post 32, so that when the card is in place, the maximum range at the given speed indicated on the 125 130

strip 49 will be the same distance from the center of the post 24.

This distance on the strip representing the known limit of range in yards, may be subdivided and the various proportional ranges marked off. As this calculation is perfectly simple, the strips furnished with my device may be marked off by the torpedo officer for the speeds and ranges of torpedoes 10 which he carries in his torpedo equipment.

With the above understanding of the construction and operation of my device it will be seen that if the enemy bar 25 be in true parallelism with the course of the enemy and 15 when the sight bar 33 is in line with the enemy at this moment, a discharge of the torpedo would score a hit.

When the apparatus is not in use, it may be desirable to lock the parts in a fixed position. For locking the enemy bar 25 in a fixed position a hole 51 is provided at one end, to be engaged by a spring-pressed plunger 52, on the arm 15, which plunger is normally held out of engagement by a pin 53 25 against the collar 54. A similar locking device 55 may be provided for the compass card 23, mounted on a dished frame 56 secured to the sleeve 9 as shown in Fig. 3. The enemy bar 25 may also be provided at 30 its outward end with a projecting plate 57 having an opening 58, through which the sight circle 23' is visible. The opening 58 is in member 59 which carries a set screw 60 by means of which it may be secured on the 35 frame 56 opposite a position on the sight circle 23' or the compass reading. This device is employed when the enemy bar 25 is manually operated. As shown in Fig. 1, the member 59 carries a pointer 61 and has a 40 small scale reading in opposite directions from zero, located at the center point. By this arrangement, the bar 25 may be conveniently moved to coincide with the changes in position of the compass card.

45 As heretofore pointed out, considerable difficulty is experienced in keeping a ship so steadily on its course that the predetermined angle of the enemy course is concentrated. In other words, each variation of the torpedo carrier tends to bring the enemy course bar 25 out of its position of parallelism to the enemy course. Even slight variations due to current or the slight movement in the steering gear may produce a variation from 50 parallel which multiplied by the considerable distance of range, produces a serious error.

Furthermore, considerable variation of 60 course is usually necessary, especially in action, and even these deliberate variations in emergencies and under excitement are difficult to report accurately and to make adjustment fall properly. I therefore have 65 made provision for automatic compensation for variation from the predetermined

course, so that the enemy bar 25 will be maintained in parallelism with the enemy course, regardless of the yawing of the ship.

I accomplish this by floating that portion of my apparatus which relates to the enemy course, namely, the compass card 23 and the enemy course bar 25, which as previously described, are relatively movable with respect to each other and to the fixed base plate 5. As shown in Fig. 3, the shaft 24, 70 which carries at its upper end the enemy bar 25, carries at its lower end an armature 62, which is in the form of a ring and secured to a collar 63 fixed on the shaft 24 by means of a ring member 64. The sleeve 22, which 75 carries the compass card 23, has fixed thereto an annular magnetic member 65 which has been hollowed to house a magnetizing coil 66, the surrounding walls forming pole 80 pieces to cooperate with the armature 62 and form a magnetic clutch. On the upper surface of the member 65 are two slip rings 67, 68, insulated therefrom by a member 69, and adapted to be engaged by brushes 70, 71, respectively, through which the coil 66 85 is energized in a well understood manner. The member 65 is also provided with a gear 72, which meshes with a gear 73 on a shaft 74. As shown in Fig. 4, the gear 73 is in 90 two parts, the lower of which is keyed to the shaft by a pin 75, and the upper of which is loosely mounted on the shaft 74, said two parts being connected by a spring 76. This arrangement is to prevent lost motion between the gears 73 and 72 as is well understood. The shaft is rotated by a repeater motor 77 adapted to be actuated from a gyroscopic compass. Preferably, three repeater motors are employed as diagrammatically indicated in Fig. 6, to increase the 95 torque, said motors being geared to the shaft 74 by suitable gears. But two of the repeater motors 77, 77' are visible in Fig. 3, from which it will be seen that shaft 74 has 100 keyed thereto a gear 78 and is driven by motor 77 through a gear 79. The other motors may drive the shaft in a similar manner. The shaft 74 also carries a gear 80 which is arranged to mesh with a crown gear 81 carried by a plunger 82, mounted in the casing 1, which latter gear is normally held from 105 engagement with gear 80 by spring 83. The shaft 82 is provided with a handle 84, by means of which the spring 83 may be compressed and the crown gear 81 brought into mesh with gear 80 and rotated to synchronize the compass card 23 with the master compass which actuates the repeaters 77, 77' and 77''. As shown in Fig. 6, these repeaters are connected in parallel, the circuit 110 being controlled by a switch 85. It will also be observed that the coil 66 is controlled by the same switch. Therefore, on the closing of the switch 85, the coil 66 is energized 115 and the enemy bar 25 and compass card 23 120

are magnetically clutched together by the means described, and the repeater circuit is closed.

As the compass card 23 is rotated by the transmitted impulse of the master compass, it is turned at every deviation of the ship from its course, and the enemy course bar 25 thus shifted to effect a readjustment of the sight bar 33. In this manner the enemy course bar is kept constantly parallel to the course of the enemy ship. By the clutch arrangement described, the compass card and enemy bar may be instantly locked together or unlocked. It is obvious that they should be locked while the enemy maintains his course, but whenever he changes, the enemy bar must be adjusted accordingly, and since changes in the enemy course may be rapid, and since the enemy course bar to be of any value whatever must be adjusted accordingly, time is a most essential element. A mechanical lock would be impractical. In my invention, the locking and unlocking of the compass card and enemy bar is practically instantaneous, that is, by simply operating the switch 85.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is:

45 1. In a torpedo director, a graduated base circle, a rotatable element having a pointer circumferentially adjustable on said circle, a graduated slide member carried by said element and having a portion adjustable radially with respect to said base circle, a sight bar pivotally mounted on said slide member for movement in a plane parallel to that of said pointer, a compass card concentric with the axis of said element, and a 50 pointer bar rotatable on the axis of said element adjustable to positions on the compass card, said pointer bar having a graduated slide member adjustable radially with respect to said base circle, said latter graduated member slidably engaging the free end of said sight bar.

60 2. In a torpedo director, a graduated base circle, a rotatable element having a pointer circumferentially adjustable on said circle, a graduated slide member carried by said

element and having a portion adjustable radially with respect to said base circle, a sight bar pivotally mounted on said slide member for movement in a plane parallel to that of said pointer, a compass card concentric with the axis of said element, a pointer bar rotatable on the axis of said element adjustable to positions on the compass card, said pointer bar having a graduated slide member adjustable radially with respect to said base circle, said latter graduated member slidably engaging the free end of said sight bar, a telescope mounted for movement with said sight bar and means for relatively displacing said telescope and bar.

70 3. In a torpedo director or the like, the combination of a compass card, a pointer bar, sighting means connected therewith, means for locking said card and bar together comprising an electro-magnetic clutch and a switch for controlling said clutch.

75 4. In a torpedo director, the combination of a sight bar, means for adjusting said sight bar, a telescope carried by said sight bar, means for adjusting said telescope with respect to said bar and means for fixing said bar at will in azimuth.

80 5. In a torpedo director, a graduated base circle, a rotatable element having a pointer circumferentially adjustable on said circle, a graduated slide member carried by said element adjustable radially with respect to said base circle, a sight bar pivotally mounted on said slide member for movement in a plane parallel to that of said pointer, a compass card concentric with said element, a pointer bar rotatable on the axis of said element adjustable to positions on the compass card, said pointer bar having a graduated slide member adjustable radially with respect to said base circle, said latter graduated member slidably engaging the free end of said sight bar, means mounted for movement with said sight bar for indicating the course of the object to be aimed at, and means for adjusting said latter means to compensate for corrections.

85 6. In a torpedo director, a graduated base circle, a rotatable element having a pointer circumferentially adjustable on said circle, a graduated slide member carried by said element adjustable radially with respect to said base circle, a sight bar pivotally mounted on said slide member for movement in a plane parallel to that of said pointer, a compass card concentric with said element, a pointer bar rotatable on the axis of said element adjustable to positions on the compass card, said pointer bar having a graduated slide member adjustable radially with respect to said base circle, said latter graduated member slidably engaging the free end of said sight bar, an electromagnetic clutch for locking said compass card and pointer

bar together, and a compass controlled repeater motor for actuating said compass card.

7. In a torpedo director, a graduated base circle, a rotatable element having a pointer circumferentially adjustable on said circle, a graduated slide member carried by said element adjustable radially with respect to said base circle, a sight bar pivotally mounted on said slide member for movement in a plane parallel to that of said pointer, a compass card concentric with said element, a pointer bar rotatable on the axis of said element adjustable to positions on the compass card, said pointer bar having a graduated slide member adjustable radially with respect to said base circle, an electromagnetic clutch for locking said compass card and pointer bar together, said latter graduated member slidably engaging the free end of said sight bar, a second member of an electromagnetic clutch secured to the lower end of said shaft to cooperate with the clutch member carried on said hollow member, and a compass controlled repeater motor for driving the latter clutch member.

8. In a torpedo director, the combination comprising a fixed base plate having a central opening and a graduated circle concentric with said opening, a sleeve on said plate surrounding said opening, a rotatable element surrounding said sleeve having a pointer circumferentially adjustable on said graduated circle, a graduated slide member carried by said element having a part adjustable radially with respect to said base circle, a sight bar pivotally mounted on said adjustable part for movement in a plane parallel to that of said pointer, a hollow member journaled in said sleeve and said

plate extending through said central opening, said hollow member carrying at its upper end a compass card concentric with said base circle, and at its lower end one member of an electro-magnetic clutch, a rotatable shaft within said hollow member carrying at its upper end a pointer bar adjustable to positions on the compass card, said pointer bar having a graduated slide member adjustable radially with respect to said base circle, said latter graduated member slidably engaging the free end of said sight bar, a second member of an electromagnetic clutch secured to the lower end of said shaft to cooperate with the clutch member carried on said hollow member, and a compass controlled repeater motor for driving the latter clutch member.

9. A structure as specified in claim 1 in combination with a casing having fixed thereto said base circle, a Cardan mounting for said casing, an electro-magnetic clutch for locking said compass card and pointer bar together located in said casing, a compass controlled repeater motor for driving said clutch, and a switch for controlling said clutch.

10. A structure as specified in claim 1 in combination with a casing having fixed thereto said base circle, an electro-magnetic clutch within said casing for locking said compass card and pointer bar together, a compass controlled repeater motor within said casing for driving said clutch, means for synchronizing said repeater motor with the transmitter, means for locking the compass card in a fixed position and means for locking the pointer bar in a certain position.

In testimony whereof I have affixed my signature.

MORTIMER F. BATES.
